UNITED STATES PATENT OFFICE.

JOHN L. THOMPSON, OF MINNEAPOLIS, MINNESOTA, ASSIGNOR OF FIVE-EIGHTHS TO WALTER A. BENNET, OF ST. LOUIS, MISSOURI, AND EDWARD McNAMEE, OF ST. PAUL, MINNESOTA.

WAGON-AXLE.

SPECIFICATION forming part of Letters Patent No. 372,581, dated November 1, 1887.

Application filed June 28, 1887. Serial No. 242,735. (No model.)

To all whom it may concern:

Be it known that I, JOHN L. THOMPSON, a citizen of the United States, residing at Minneapolis, in the county of Hennepin and State 5 of Minnesota, have invented certain new and useful Improvements in Wagon-Axes; and I do hereby declare that the following is a full, clear, and exact description of the same.

The object of my invention is the production 10 of a serviceable axle that is light, strong, and inexpensive. This object I accomplish by the construction illustrated in the accompanying drawings, in which—

Figure 1 shows a rear elevation of the axle 15 with its spindles, the bolster, and ends of the hounds and reach. Fig. 2 is an enlarged plan view of a portion of the inverted axle and its spindle. Fig. 3 is a longitudinal sectional view of the same on the line X X, Fig. 2; and Fig. 4 2c is a transverse section on the line Y Y of Fig. 2.

A in the drawings designates a channel-iron bar serving as the axle; B, a wooden cap-bar secured to the top of the axle, and C the usual bolster.

25 c c are the hounds, and c' the reach.

The spindles D are formed on separate pieces, the square stocks d of which fit closely in the ends of the channel of the axle, and bands or axle-clips b, around the stocks d and axle and 30 cap-piece, unite these parts. These parts are further secured together and to the bolster by bolts a, extending from the flattened portion d' of the spindle-stock to the top of the bolster

through the hounds. Additional bolts, e, are passed through the web of the channel-iron and 35 the flat part d' of the spindle-stock. The heads n of the bolts a and e may be made to fit within the channel of the axle, so that they cannot turn, and the nuts for the bolts may be at the upper ends, those for the bolts a in mortises in 40 the top of the bolster, and those for the bolts e on top of the axle and fitting in mortises in the under side of the cap-piece B. If preferred, however, the nuts n' may be on the lower ends 45 of the bolts and adapted to be turned in the channel of the axle, as shown in the drawings.

An axle constructed as described possesses the requisites of strength, lightness, and cheapness.

Having described my invention, what I 50 claim, and desire to secure by Letters Patent, is—

A wagon-axle consisting of a channel-iron bar having a rectangular channel and placed with its web uppermost, and spindles having 55 square portions fitting in the ends of said channel and flat portions extending within the channel, and bolts through said flat portions of the spindle stocks and the web of the channel-iron, and adapted to secure the same together and to the bolster, substantially as set forth.

JOHN L. THOMPSON.
